(57) **CLAIM**

The ornamental design for a component part of a caliper, as shown and described.

DESCRIPTION

FIG. 1 is a front view of a component part of a caliper according to our design, with environmental parts shown in broken lines;

FIG. 2 is a rear view thereof;

FIG. 3 is a top plan view thereof;

FIG. 4 is a bottom view thereof;

FIG. 5 is a left side view thereof;

FIG. 6 is a right side view thereof; and,

FIG. 7 is a perspective view thereof.

The broken line showing in FIGS. 1-7 is for illustrative purposes only, and does not form part of the claimed design. Any indicia such as measurement indicia, control button indicia and indicia of a proprietary nature, is hereby disclaimed and forms no part of the claimed design.
